UNITED STATES PATENT OFFICE.

ERWIN HARRIS OAKMAN, OF ATLANTA, GEORGIA.

INKWELL.

1,320,903.

Specification of Letters Patent. Patented Nov. 4, 1919.

Application filed November 25, 1918. Serial No. 264,049.

To all whom it may concern:

Be it known that I, ERWIN H. OAKMAN, a citizen of the United States, residing at Atlanta, in the county of Fulton and State 5 of Georgia, have invented a new and useful Inkwell, of which the following is a specification.

The device forming the subject matter of this application is a fountain ink well, 10 and one object of the invention is to provide novel means whereby a penholder may be supported in the basin of the well.

Another object of the invention is to provide novel means on the inner receptacle for 15 forming, at times, a pen rack, and for forming, at other times, a support for the inner receptacle.

It is within the province of the disclosure to improve generally and to enhance the 20 utility of devices of that type to which the present invention appertains.

With the above and other objects in view, which will appear as the description proceeds, the invention resides in the combination 25 and arrangement of parts and in the details of construction hereinafter described and claimed, it being understood that, within the scope of what is claimed, changes in the precise embodiment of the invention 30 shown can be made without departing from the spirit of the invention.

In the accompanying drawings:—

Figure 1 is a top plan; Fig. 2 is a section on the line 2—2 of Fig. 1; the closure for 35 the ink basin being removed; Fig. 3 is a section on the line 3—3 of Fig. 1, the closure for the ink basin being removed; Fig. 4 is a section on the line 4—4 of Fig. 2; and Fig. 5 is a perspective view showing the closure for 40 the ink basin.

The device forming the subject matter of this application may be made of any desired material and includes an outer casing 1 comprising a back 2, a front wall 3 and side 45 walls 4. The casing 1 includes a bottom 5 which is spaced above the lower edges of the back 2, the wall 3, and the walls 4. The end walls 4 of the outer casing 1 are supplied in their lower edges with notches 6 which, giving access to the fingers of an operator, permit the outer casing 1 to be handled readily. Below the bottom 5, the wall 3 is thickened as shown at 7. A notch 50 8 is formed in the wall 3, the notch being open from the upper edge of the wall 3 to the bottom 5. A conical basin 10 is con-

nected with the wall 3, about the notch 8 and includes a bottom 11. Between the bottom 5 of the outer casing 1 and the bottom 11 of the basin 10, the notch 8 extends but part 60 way through the wall 3 opposite to the thickened portion 7, to fashion a seat 9, the function of which will be alluded to hereinafter. It is to be observed that the outer wall of the basin 10 includes converging parts 12, forming a pronounced reduced seat 14 located opposite the seat 9. The invention comprises an inner receptacle 15 including a top 16, a back 17, a front 18 and sides 19. The top 16 of the inner receptacle 15 projects beyond 70 the back 17, the front 18 and the sides 19 to form a flange 20 overhanging the periphery of the outer casing 1 when the inner receptacle is inverted in the outer receptacle. The front 18 of the inner receptacle 15 is 75 provided with a notch 21 communicating with the basin 10 by way of the notch 8 in the wall 3 of the outer casing 1.

Transverse ribs 22 are mounted on the top 16 of the inner receptacle 15 and are 80 provided with notches 23 which form a pen rack when the inner receptacle is disposed within the outer receptacle. The notches 23 form lugs 24. A removable closure 25 fits in the basin 10 and is provided with a projection or handle 26.

In practical operation, when the inner receptacle 15 is mounted in the outer casing 1, the ink in the inner receptacle flows through the notch 21 and the notch 8 to the 90 basin 10, a barometric feed being provided, and ink being supplied to the basin when the ink in the basin is depleted. A pen holder may be set upright in the basin 10, the lower end of the pen holder being received in the 95 seat 9, and the intermediate portion of the pen holder being received in the seat 14, the pen holder being supported adequately in this way.

During the filling of the inner receptacle 100 15, the inner receptacle is removed from the outer casing 1 and is turned upside down, so that its open end is uppermost. The receptacle then is supported on the lugs 24. The inner receptacle 15 is spaced from the support on which it is mounted, the lugs 24 bringing about this result, and it being possible to engage the fingers beneath the flange 20 for the purpose of lifting or handling the inner receptacle. It is to be observed that 105 110 the ribs 22 and the notches 23 exercise a double function, since the notches 23 form a

pen rack when the inner receptacle 15 is disposed within the outer casing 1, and, further, form lugs 24 which support the inner receptacle in a way hereinbefore pointed out, when the inner receptacle is removed from the outer casing, and is turned upside down, during the filling operation.

Having thus described the invention, what is claimed is:—

10. An ink well comprising an outer casing having a bottom, and including a front wall; a conical basin connected with the front wall and having its lower end disposed below the bottom of the casing, the front wall having a notch extended entirely through the front wall to the bottom of the outer casing, and extended part way through the front wall
- 15

from the bottom of the outer casing to the lower end of the basin, to form a seat for one end of a pen holder, the outer wall of the 20 basin being extended outwardly, opposite to the seat, to form a pronounced reduced seat for the intermediate portion of a pen holder; and an inner receptacle inverted in the outer casing, the inner receptacle having an opening 25 communicating with the basin by way of the notch.

In testimony that I claim the foregoing as my own, I have hereto affixed my signature in the presence of two witnesses.

ERWIN HARRIS OAKMAN.
